SPRAY DRYING APPARATUS

Edward Van der Pyl, Holden, Mass., assignor to Norton Company, Worcester, Mass., a corporation of Massachusetts

Application May 6, 1953, Serial No. 353,420

5 Claims. (Cl. 159—4)

The invention relates to spray drying apparatus.

One object of the invention is to provide a simple and thoroughly practical spray drying apparatus. Another object is to provide a spray drying apparatus for drying a slip or slurry to form particles or pellets of a predetermined size. A further object is to provide apparatus whereby the size of the particles or pellets may be varied in size. Another object is to provide a water-cooled spray head to prevent drying of the slip or slurry. Another object is to provide means for recirculating any desired portion of the slurry to avoid segregation. Another object is to automatically control the flow of slurry to compensate for any inconsistency, that is, percent of solids. Another object is to provide means to circulate fluid through the spray head for cleaning purposes to clean-out before running a different material through the dryer. Another object is to provide a spray head which may be used in either an upper-draft or a down-draft spray dryer. Another object is to provide a nozzle that will spray a highly abrasive material without detrimental wear in the slurry orifice. Another object is to provide a nozzle through which a slurry may pass at a low velocity and impinged by air at high velocity after it leaves the nozzle so as to minimize wear in the nozzle parts.

Other objects will be in part obvious or in part pointed out hereinafter.

The accompanying drawings illustrate efficient apparatus for making the particles but our process is not limited to the use of this particular apparatus. In the drawings,

Fig. 1 is a front elevation of spraying and drying mechanism, certain portions being shown in section;

Fig. 2 is an axial sectional view, on an enlarged scale, of the spraying head and connections;

Fig. 3 is a cross sectional view, on an enlarged scale, taken approximately on the line 3—3 of Fig. 2;

Fig. 4 is a partial sectional view of the nozzle of Fig. 2 but showing an arrangement for producing larger particles;

Fig. 5 is a vertical sectional view, on an enlarged scale, taken approximately on the line 5—5 of Fig. 2; and

Fig. 6 is a diagrammatic view, showing an automatically actuated valve and the controls therefor for automatically regulating the by-pass of slurry.

Referring to Fig. 1, a mixing bowl 10 has therein a multiple vane paddle 11 on the lower end of a vertical shaft 12 mounted in bearings 13 and connected by coupling units 14 to the output shaft 15 of a reduction gear unit 16 driven by an electric motor 17. The mixing bowl 10 is charged with metal oxide powder and water and the rotation of the paddle 11 produces and maintains a slip with the fine particles well and evenly distributed therein. As one example of practising the invention, I took 95 parts by weight alumina powder, 5 parts by weight plastic ball clay powder, 4 parts by weight powdered dextrin, and 1/2 part by weight powdered carboxy methyl cellulose. These were mixed together in a tumbling barrel for about one-half to one hour, or until a uniform

2

mixture was obtained. Water, 100 pounds, was then put in the kettle followed by 200 pounds of the above dry material. After mixing about an hour, the mixture was considered to be too viscous to flow properly, and therefore 12 pounds additional water was added. After further mixing the mixture was considered satisfactory. Oxides or hydroxides or other compounds readily decomposable by heat to form oxides can be used as metal oxide source materials. The metal compound can be that of aluminum, barium, beryllium, calcium, chromium, cobalt, columbium, magnesium, manganese, molybdenum, nickel, silicon, strontium, tantalum, thorium, tin, titanium, uranium, vanadium, zinc, zirconium. I can also use spinel, mullite or various mixtures including many minerals.

The suspension or slip in the mixing bowl 10 is pumped by a diaphragm pump 20 to a two-fluid spray nozzle unit 21 (Fig. 2). Referring to Fig. 1, the connections including shut-off gate 23 which, when open, allows the slip to flow from the bowl into a hose 24 which is connected to a pump 20, hose 25 which is connected to the output side of a diaphragm pump 20, a T-union 26 and a pipe 27.

The two-fluid spray nozzle is preferably a water-cooled nozzle to prevent drying of the slurry or suspension during passage through the nozzle. As illustrated in Fig. 2, the pipe 27 is welded into an aperture 28 formed in a laterally projecting boss 29 of a housing 30. Similarly a pipe 31 is welded within an aperture 32 formed in a laterally projecting boss 33 of the housing 30. The housing 30 is provided with a central passage 34 which connects the pipe 27 with the pipe 31. The slurry or suspension being forced through the pipe 27 by the pump 20 is forced upwardly through a passage 35 formed in a slurry nozzle 36. The pipes 27 and 30 are water-cooled in the following manner:

A tube 37 is arranged concentric with the pipe 27 and is welded onto the outer peripheral surface of the boss 29. A collar or end cap 38 fits on the pipe 27 and within the tube 37 and is welded to both the pipe 27 and the tube 37 so as to form a water cooling chamber 39 surrounding the pipe 27.

Similarly a tube 40 is arranged concentric relative to the pipe 31 and is welded onto the external cylindrical surface of the boss 33. A collar or end cap 41 fits on the pipe 31 and within the end of the tube 40 and is welded to both the pipe 31 and the tube 40 to enclose the right hand end of a water-cooling chamber 42. In order to facilitate circulation of cooling fluids, such as water, the housing 30 is provided with a plurality of holes 43 (Figs. 2 and 5) which connect the chamber 39 with the chamber 42. Coolant may be passed through a pipe 44, into the chamber 39, through the holes 43, through the chamber 42 and out through the pipe 45 so as to cool a slurry or suspension of material passing within the pipe 27 and the pipe 31.

The diaphragm pump 20 may be operated in any suitable manner; as shown an electric motor 46 operates a reduction gear unit 47 which drives a belt 48 which drives a pulley 49 secured to which is an eccentric 50 operating a connecting rod 51 which operates the diaphragm 52. A long cylinder 55 functions as a dome or accumulator to keep the flow as steady as possible. On this may be mounted an air pressure gauge 56.

A pipe 57 is connected to a water main and to a valve 58 which is connected to a pipe 59 which is connected to a T-union 60. The T-union 60 is connected by a hose 61 to a valve 62 which is connected to the T-union 26 on the left hand end of the pipe 27 (Fig. 1). The valve 62 is normally closed and may be opened manually to facilitate flushing out the pipes 27 and 31, and also the nozzle unit 21.

Referring again to Fig. 1, the pipe 31 is connected to a valve 69. The pipe 45 is connected to a hose 70 which is connected to drain.

The T-union 60 is connected by a hose 71 to the pipe 44 and so therefore, when the valve 58 is open, water flows through the pipe 44, through the chamber 39, through the holes 43, through the chamber 42 and through the pipe 45 into the hose 70 to drain. The purpose of this flow of water is to cool the pipes and unions inside of a funnel 74 to prevent drying of the slurry before passing through the nozzle as, during operation of the process, the atmosphere within the funnel 74 is hot. Some water can be added to the slip, if desired, by opening the valve 62, more or less.

Still referring to Fig. 1, a pipe 75 is connected to an air pressure main and to a valve 76 which is connected by a pipe 77 to a water trap 78 which is connected by a pipe 79 to a reduction valve 80 which is connected by a pipe 81 to a T-union 82 which is connected by piping 83 to the housing 30.

Referring to Fig. 2, fluid under pressure from the pipe 83 passes to the housing 30 into an annular air chamber 85 which is in communication with a plurality of perforations or holes 86 formed in a diffusion plate 87. The perforations or holes 86 in the diffusion plate 87 serve to diffuse the air under pressure passing from the chamber 85 into the nozzle aperture. The thickness of the diffusion plate 87 serves to determine the relative positions of the nozzle aperture 90 and the slurry nozzle orifices 91, thereby providing means for adjusting the combined actions of the nozzles. The diffusion plate 87 has a central aperture which fits around the outer periphery of the slurry nozzle 36 and is held in position on the housing 30 by a cap 88 which is preferably screw-threaded onto the housing 30 to facilitate changing the diffusion plate 87 when desired. Air passing through the perforations or holes 86 enters a chamber 89 and is forced upwardly through a frusto-conical nozzle aperture 90 so as to form an upwardly converging jet of air surrounding the orifice 91 of the slurry nozzle 36. This slurry or slip issuing from the orifice 91 of the slurry nozzle 36 is immediately atomized by the air issuing from the chamber 89. Consequently the slip becomes a spray of particles which are directed upwardly through a hollow ring 92 (Fig. 1) open on the upper side and from it hot gas is being distributed upwardly. We will now describe the means for producing and directing the flow of hot gas.

Referring to Fig. 1, a pipe 95 is connected to a gas main and to a valve 96. The valve 96 is connected by a pipe 97, elbow 98 and pipe 99 to a carburetor 100 which has adjustable air inlets, the shape of the carburetor and the location of the air inlets being such as to cause air to be entrained into and mixed with the combustible gas entering the carburetor 100; the carburetor 100 is connected by an elbow 101 and short pipe 102 to a second carburetor 103 having fixed air inlets 104 for the admission of additional air. The carburetor 103 is connected by an elbow pipe 105 to the hollow ring 92 and supports it. Consequently when the mixture of air and gas is ignited, an upwardly directed ring of flame is produced above the hollow ring 92; the spray enters this hollow ring of flame and moves upwardly therewith and eventually, because of the rapid uprush of gas and hot air prevents the material from falling back through the ring 92, the spray spreads out in expanding funnel shape and falls downwardly into the funnel 74. The locus of the upwardly directed ring of flame which also can be likened to a funnel and the funnel shaped spray of slip is in a large hollow cylinder 110 which can be made of metal and it conveniently has a removable flat cover 111. This metal cylinder 110 is secured in any suitable manner to the funnel 74 so that the cylinder 110 and funnel 74 together constitute a large drying chamber, cylindrical above the hollow ring 92 and conical below it.

In order to control the size of the particles or pellets

formed by the spray drying apparatus, it is desirable to control the stream of air under pressure passing from the conical aperture 90. The upper end of the slurry nozzle 36 is provided with an external frusto-conical surface 36a, the vertex angle of which is approximately 60°. The vertex angle of the conical aperture 90 has been illustrated as approximately 35°. Depending upon the material being treated and the resulting product desired, the latter angle may be varied from 35° to 9° by providing a series of caps 88 with the desired angle for the conical aperture 90. By varying the relationship of the frusto conical surface 36a and the conical aperture 90, the path of air under pressure passing from the spray nozzle may be varied so as to produce variations in the size of the particles or pellets produced.

The position of the conical aperture 90 may be varied relative to the frusto-conical surface 36a by providing diffusion plates 87 of different thicknesses so as to raise or lower the position of the aperture 90 relative to the surface 36a. As illustrated in Fig. 2, the diffusion plate 87 positions the conical aperture 90 so that the upper face of the cap 88 lies in the same plane with the upper end of the slurry nozzle 36 so that air passing from the nozzle converges upon the stream of slurry directly above the nozzle so as to break down the slurry into relatively fine particle or pellet sizes. If it is desired to increase the size of the particles or pellets produced, a thinner diffusion plate may be employed, as shown in Fig. 4, so that the slurry nozzle 36 projects above the upper surface of the cap 88. In the latter positions of the conical surface 36a and 90, air passing from the nozzle impinges upon the stream of slurry at a greater distance from the nozzle so that the air velocity on the stream of slurry is somewhat reduced thereby breaking the slurry down into larger particle or pellet size. The size of the particles or pellets produced may also be varied by using a cap 88 having a conical aperture 90 with a different vertex angle. With a smaller vertex angle the air passing through the nozzle will impinge upon the stream of slurry at a greater distance from the nozzle thereby effecting a reduced velocity of air which serves to break down the slurry into particles or pellets of larger size.

I provide means for removing the gases of combustion after they have to a certain extent given up their heat and at a place to promote the circulation above indicated. To that end, and still referring to Fig. 1, I have provided a double elbow pipe 115 which enters the funnel 74 through a hole just large enough to receive it and extends by way of a portion 116 which becomes wider in the vertical dimension without increasing in width in the horizontal dimension, to a cyclone separator 117 which, as cyclone separators are well known, need not be described in detail. The cyclone separator eliminates from the moving gases most of the entrained solids therein which fall downwardly into a metal receptacle 120. The gases move upwardly through an elbow pipe 121 connected to the cyclone separator 117; the other end of the elbow pipe 121 is connected to the inlet end of a centrifugal blower 125 the outlet of which is connected to a pipe 126 leading to a chimney or the like. A damper 127 operated by an arm 128 the end of which is bent over and can be placed in any one of a number of holes 129 in a plate 130 for adjusting the position of the damper 127 is preferably provided to control the amount of air being drawn from the funnel 74 by the blower 125.

By closing the valve 69 I can force all of the slip pumped by the pump 20 to be ejected from the orifice 91. On the other hand, by opening the valve 69 more or less, I can allow more or less of the slip to by-pass the passage 35 of the spray nozzle unit 21 to be returned to the mixing bowl 10 by way of a long hose 135 which, as clearly shown in Fig. 1, extends from the valve 69 to a position just above the bowl 10.

As shown in Fig. 1 a manually operable valve 69 is provided for controlling the by-pass of slurry through the

by-pass pipe 135 so as to regulate the amount of slurry passing through the slurry orifice 91 of the slurry nozzle 36.

If desired, an automatic control may be provided such as for example, an automatic diaphragm-actuated valve 106 (Fig. 6) in the by-pass pipe 135. This diaphragm-actuated valve 106 may be any of the well known commercial type valves. A controlling mechanism is provided for controlling the actuation of the valve 106. This mechanism may comprise a thermocouple 107 located in the pipe 116 through which exhaust gases and pallets pass. The thermocouple 107 is connected to a pneumatic temperature recorder-controller 108, such as, for example that manufactured by the Wheelco Instrument Co. of Chicago, Illinois. The power lines 109 supply current to the recorder-controller 108. A pipe 112 connected to any suitable source of air under pressure is supplied to the recorder-controller 108. This mechanism as shown diagrammatically in Fig. 6 is arranged so that if the temperature of the gases exhausting through the pipe 116 from the funnel 74 increases, the thermocouple 107 through the recorder-controller 108 will actuate the diaphragm valve 106 to cut down the by-passing slurry through the pipe 135 so as to force a greater quantity of the slurry upwardly through the slurry nozzle 36 and the orifice 91 thus introducing more moisture into the dryer to be dried and vice versa.

I provide means for discharging the pellets formed from the funnel 74 without materially disturbing the atmosphere in the funnel 74 and cylinder 110. To that end I provide a hollow rectangular downward extension 138 of the funnel 74 (which has a small opening on the bottom) and in this extension 138 is a revolving gate 139 which may have the shape of a paddle wheel and which is mounted on a rotatable shaft 140. A pulley 141 secured on the shaft 140 is driven by a belt 142 from a pulley 143 on the output end of reduction gearing 144 driven by an electric motor 145. It will readily be seen that the accumulation of particles in the bottom of the funnel 74 is intermittently but regularly discharged into any suitable collecting container such as the refractory sagger 150. In this connection it should be noted that the valve 96 and the damper 127 can be so adjusted that the pressure of the hot gases within the funnel 74 and the cylinder 110 is substantially at atmospheric pressure or, preferably, just barely below it so as to avoid discharging gases of combustion into the room where the apparatus is located.

Preferably I provide various devices for measuring the parameters of the process, for example an air gauge 151 connected to the T-union 82, a door 152 having a glass pane 153 for viewing the interior of the cylinder 110, and the door 152 is shown as mounted on a hinge pin 154 suitably secured to the cylinder 110 and held in closed position by a wing nut 155. I may also provide a thermometer 160 on the elbow pipe 121 to measure temperature therein and a thermometer 162 located in the funnel 74 but readily removable therefrom for reading.

By this process I make various particles sizes depending upon the adjustment of the spray nozzle and other factors, and these may include particles as large or even larger than No. 20 grit size down to as small or even smaller than No. 320 grit size. With suitable equipment designed to produce an extremely fine spray or fog, it is believed that a large part of the product can be made finer than No. 320 mesh when desired. Of course for the smaller sizes the particle size of the metal oxide should be small as the ultimate particles are aggregates of very many individual oxide particles. In general increase of the air pressure by adjusting the air valve 76 and the reduction valve 80 decreases the particle size of the product 170 in the sagger 150. Increase of the volume of gas being burned as by setting the valve 96 accelerates the drying which may be required for maximum production and for the larger particle sizes. The

amount of slurry being sprayed can, as already indicated, be controlled by the valve 69 up to the maximum amount being delivered by the pump 20. There are thus many variables and the apparatus can be adjusted to produce particles of the desired size and when that has been done further adjustment is made to ensure that they are dry enough and not too dry and also that each one is roughly a sphere. The spray drying process described will, when the proper adjustments have been made, produce substantially spherical particles or pellets within the size limits indicated.

The pump 20 is preferably a low volume low velocity pump for passing a highly abrasive slurry at a relatively low velocity through the aperture 36 and the orifice 91 of the slurry nozzle 36 thereby reducing wear in the orifice to a minimum. In applicant's apparatus the slurry and air under pressure mix at a point outside the nozzle thus aiding in minimizing abrading action of the slurry on the nozzle parts.

The spray nozzle unit 21 has been illustrated in Fig. 1 in an up-draft spray drying apparatus. This spray nozzle unit 21 is equally applicable to a spray drying apparatus in which a down-draft is employed.

The apparatus disclosed in this application is somewhat similar to that disclosed but not claimed in the co-pending application, Serial No. 325,862 filed December 13, 1952, and now abandoned.

It will thus be seen that there has been provided by this invention a process for the manufacture of spherical particles according to which the various objects hereinabove set forth together with many thoroughly practical advantages are successfully achieved. As many possible embodiments may be made of the above invention and as many changes might be made in the embodiments above set forth, it is to be understood that all matter hereinbefore set forth or shown in the accompanying drawings is to be interpreted as illustrative and not in a limiting sense.

I claim:

1. In a spray drying apparatus, a vertically-arranged drying chamber, a slurry feed tube passing through said chamber, a two-fluid spray nozzle therefor comprising a slurry nozzle operatively connected with a central portion of the slurry feed tube, an air nozzle surrounding the discharge end of said slurry nozzle, the axes of said nozzles being arranged in axial alignment with the vertical axes of said chamber, a slurry tank, means including a pump to feed slurry from said tank to one end of said feed tube and nozzle, means to feed a controlled stream of air under pressure to said air nozzle, a by-pass pipe connected between the other end of said slurry feed tube and said tank, a valve between the other end of said feed tube and said by-pass pipe to regulate back pressure within the slurry tube so as to vary the quantity of slurry passing through the slurry nozzle, and a ring-shaped burner surrounding said nozzle to produce a circular flame to aid the nozzles in producing a relatively high funnel shaped spray of slurry to facilitate the drying operation.

2. In a spray drying apparatus, a vertically-arranged cylindrically-shaped drying chamber, a slurry feed tube passing through one end of said chamber, a two-fluid spray nozzle therefor comprising a slurry nozzle operatively connected with a central portion of the slurry feed tube, an air nozzle surrounding the discharge end of said slurry nozzle, the axes of said nozzles being arranged in axial alignment with the axis of said drying chamber, means to cool said slurry tube as it passes through said chamber to prevent drying and caking of slurry passing through said tube, a slurry tank means including a pump to feed slurry from said tank to one end of said feed tube and nozzle, means to feed a controlled stream of air under pressure to said air nozzle, a by-pass pipe connected between the other end of said slurry feed tube and said tank, an automatically actuated valve in said by-

pass pipe automatically to vary back pressure within the slurry feed tube by varying the amount of by-passed slurry so as to regulate the quantity of slurry passing through the slurry nozzle, means including a thermostat actuated by exhaust gases from the dryer and operative connections between said thermostat and said valve automatically to control said valve.

3. In a spray drying apparatus, a vertically-arranged cylindrical drying chamber, a slurry feed tube passing through said chamber, a two-fluid spray nozzle therefor comprising a slurry nozzle operatively connected therewith at a central portion thereof, an air nozzle surrounding the discharge end of said feed nozzle, a slurry tank, means including a pump to feed slurry from said tank to one end of said feed tube, means to feed a controlled stream of air under pressure to said nozzle, the axes of said nozzles being positioned in alignment with the axis of said drying chamber, a by-pass pipe connected between the other end of said feed tube and said tank, an automatically actuated diaphragm throttle valve in said by-pass pipe to vary the pressure within the slurry tube by controlling the amount of by-pass slurry thereby to regulate the quantity of slurry passing through the slurry nozzle, means including a thermostat actuated by gases from the drying chamber to control said valve, and a ring shaped burner surrounding said nozzles to produce a circular flame, said burner and nozzles being positioned so as to produce a relatively high funnel-shaped spray of material to facilitate the drying operation.

4. In a spray drying apparatus comprising a vertically-arranged cylindrical drying chamber, a slurry feed tube passing therethrough, a two-fluid nozzle therefor including a housing located mid-way of said tube, a vertical aperture in said housing, a slurry nozzle supported in said aperture having a central aperture for discharging a slurry, an air nozzle surrounding the discharge end of said slurry nozzle, the axes of said nozzles being positioned in alignment with the axis of said drying chamber, a slurry tank, means including a pump to feed slurry from said tank to one end of said tube and nozzle, means to feed a controlled stream of air under pressure to said air nozzle, a tube surrounding said slurry feed tube as it passes through the drying chamber to form a cooling chamber, means to circulate a cooling fluid therethrough, a by-pass pipe connected between the other end of said feed tube and said tank, said cooling chamber serving

to prevent drying and caking of slurry passing through said tube to said nozzle and said by-pass pipe, an automatically actuated valve in said by-pass pipe to facilitate regulation of back pressure of slurry within the slurry tube by controlling the amount of by-pass slurry thereby to regulate the quantity of slurry passing through the slurry nozzle, and means including a thermostat actuated by exhaust gases from the drying chamber to control said valve.

5. A nozzle for spray drying apparatus comprising a slurry feed tube, a two-fluid nozzle therefor including a housing operatively connected to said tube, a vertical aperture in said housing, a slurry nozzle supported in said aperture having a central aperture for conveying a slurry, said hollow nozzle having a downwardly flaring external frusto-conical surface on its outer periphery at the upper end thereon, an annular air chamber in said housing surrounding said vertical aperture, a perforated diffusion plate enclosing the upper end of said chamber and a cap to hold said plate on said housing, said cap having an internal frusto-conical aperture forming an air nozzle, said nozzles being arranged so that slurry passing through the slurry nozzle is picked up by air under pressure from the air nozzle after it leaves the slurry nozzle so as to minimize wear on the nozzles, the thickness of said plate determining the relative positioning of said frusto-conical surfaces to facilitate varying the action of said nozzle on a slurry passing therethrough so as to facilitate varying the size of particles or pellets produced.
